Setters' Patent

This schedule referred to on the following Patent and making part of the same, containing a description and the mode of the said Edward Alger himself of his mode of casting large iron Rollers for Rolling iron, &c.

The invention of this improvement in casting large iron Rollers, or rolling iron, and other metals into wheels, axles, and bars, consists in the first place in manufacturing the moulds in such a manner as to have the rollers drawn cast iron moulds, and the shoulder and quillings of the roller ^{and} stand, and in the second place in the method to be observed in pouring the melted iron into the moulds, in order to have the rollers most perfectly drawn strong and firm from cold steel, in the surface of the body of the roller.

And first. The part of the moulds, in which the body of the Roller is cast is called the cylinder and is made of cast iron. This part is six inches thick and as long and large in diameter as is required in the Roller to be cast in it. This cylindrical part of the moulds is made in two pieces, or halves, each half being half a circle, and are made to fit together with a good joint and fastened together with strong key bolts, which go through ledges, cast on the circular sides, close to the joint of each piece. When thus fastened together by said key bolts, which must be well fitted, the inside of it must be turned perfectly smooth and true and polished in a lathe, and the ends are also turned true and smooth. The inside diameter must be the same at both ends. When the Roller is cast and cool, the said cylinder is unkeyed and taken apart, otherwise it would be very difficult to get the roller out of the moulds. This part of the moulds, must be made very perfect on the inside, in order that the Roller drawn when cast therein may be equally perfect. To each end of this cylinder are also fastened with key bolts, two other conical cylinders of cast iron which contain the sand in which the sand and which the quillings, and shoulders of the roller are moulded and cast. These conical cylinders, called the top and bottom moulds, are the

should be cast with a wide rim or flange at their largest ends where
now opposite turned in a lathe to make a fit with a good joint to the
end of the said cylinder, each of the said neck pieces of the mould is fast
to the end of the said cylinder by these big bolts, well fitted to each side
as steadily as possible, or handle, must be fastened on each side of
said cylinder and said top and bottom necks, or to handle them
with ease and safety. The base of these neck pieces of the moulds
about a quarter smaller at their smaller ends than the base of the
mould, and are also much thinner than the said cylinder to which ends
are fastened. The inside of these neck pieces may have several small
cast iron to prevent the said pieces falling out. To the small end
of the bottom neck piece a rim is cast on it to fix on it a bottom plate
of cast iron by key bolts. This said bottom piece serves as the base on
the whole mould is sufficient to be in a perpendicular position when casted.
The cast iron part of the moulds being thus made the bellows for the
air is then put into the moulds, which are then joined together and the
body of said bellows must fit the inside of the cylindrical part of the
the said neck as is used in casting iron, is then fitted into the neck
of the moulds, and surrounded in sufficiently from round the yoke or
said plate, and against the shoulders of the body of it. The said
top piece which serves as the base of the moulds is then keyed or firm
to the top part of the moulds being first or vice versa longer than the
iron of the roller to be cast therein. In a hole made in the said iron
of the size of the yoke or said iron, and in the same direction to the top of it, a
hole being filled with melted iron, when the roller is cast dropping
concentration of the yoke or said roller below as they gradually cool
and thereby retains the clearest yoke or said iron strong when the roller
is cut off, the moulds are then made and joined together, so that when the
iron cast and joined it may be taken out by unfastening the moulds, the
cylindrical part of which being the part of the iron mould is when the base
of the roller is cast or built of with ends from the body of the roller,
therefore said yoke or said iron stand on the casting platform of the
mould

place the moulds are to be placed in the moulds and the sand being removed
leaving the long part of it to rest the iron in more comfort than as it is all
at once it would be too large of the said body of iron to be
To the lower neck piece of the mould is placed a tube the whole of which
communicates with the lower end of the cavity of the thing moulded and
the other part of the lower neck, or perpendicular high equal to the
height of the moulds. The melted iron is poured into this tube and
colder at the bottom of the mould instead of being pour'd at the top
of the moulds as is customary. This tube is made in two pieces and put
together with rings or other fastenings somewhat like a fore-iron mould
The inside of this tube is coated over with clay so that after the roll
is in, and the cast iron in this tube may be easily taken out by taking
said tube ap'st longitudinally. The top of this tube is made like a funnel
so as to be convenient in pouring the melted iron into it. Care must
be taken to have the longitudinal joints of the said cylinder and the joints
of the two neck pieces on the ends of said cylinder made tight so that
the melted iron may not leak out, and also to have the inside of
said cylinder kept clean and made sizing hot so to the surface of
the body of the roller may be cast perfectly smooth and free from any
perfection. Secondly, the method to be observed in casting said
rollers in these moulds is this viz. to have a circle or iron cut out of a
fine board, or other durable wood so as to fit the inside of the body of
said moulds. This wooden circle is put into the said cylinder or body of
the moulds and the top neck of the moulds is left off until the mol-
ten iron when pour'd has fill'd the body of said mould and said
the said wooden circle to the top when it is taken off and the said
top neck of the mould is put on layed down and then the melted iron
is again pour'd in until the mould is fill'd. The use of this wooden
circle is to keep the impurities on top of the melted iron from the sides
of the body of the moulds and thereby prevent them from being cast in
the surface of the roller and thus render such effects as important
object and keeps all the impurities on the middle of the melted iron
and when the mould is full they may then be taken off and clean out

the body of the Rollers when they are to be a company. The greatest expense and time lost will be to have them made of thin iron and then to have to have thick plates and bars and to have them sent from hence to have to manufacture the Rollers to have them to have the surface of the body of the Rollers to have the quidgeons as well as the body of the Rollers cast solid. They externally as well as internally and the surface of the Rollers must be smooth true and free from cold shilly. Rollers cast in moulds of the situation and with this method well known have been found to have these important qualities and which under these dispensers to have in any other manner. Care must also be taken to put the moulds together in one way. So as to prevent any mistake. In moulds they cast should may be cast the Rollers for rolling iron into round and square bars. From this use it would only be necessary to have the said cylinder in which the body of the roller is cast turned out with proper circular and square process as may be wanted in the Rollers. The Rollers are cast in the perpendicular position with the quidgeon having a square cavity and by which to put them in operation downward or at the bottom when cast. If the moulds are well made and the pattern of the Rollers well made the Rollers will be cast at once as to admit them being ground in a common or half round piece of cast iron with sand and water and finished with coarse emery without the trouble of turning said Rollers with edge tools which requires much time in consequence of the surface of said Rollers. And to grind the Rollers true in this way it is necessary to have them run very rapidly in the lathe.

Yours Affectionately

Wm. H. Allen
At night.
